UNITED STATES PATENT OFFICE.

JAMES MILNOR HICKS, OF SUMMIT, NEW JERSEY, ASSIGNOR OF ONE-HALF
TO ABBOT AUGUSTUS LOW, OF HORSESHOE, NEW YORK.

SEALING-CAP FOR VESSELS UNDER PRESSURE.

SPECIFICATION forming part of Letters Patent No. 746,332, dated December 8, 1903.

Application filed July 29, 1903. Serial No. 167,381. (No model.)

To all whom it may concern:

Be it known that I, JAMES MILNOR HICKS, a citizen of the United States of America, residing at Summit, Union county, New Jersey, have invented certain new and useful Improvements in Sealing-Caps for Vessels Under Pressure, of which the following is a specification.

My invention relates to means for sealing vessels containing liquids under pressure; and it consists in certain elements and combinations hereinafter specified and claimed.

In order that those skilled in the art to which my invention appertains may understand, construct, and use my invention, I will proceed to describe it, referring to the drawings herewith, in which—

Figure 1 shows a bottle and closing-cap in longitudinal section with the stopper being forced to place beneath the upper surface of the cap through a central opening thereof by means of a bottle-filling apparatus. Fig. 2 shows a similar view in which the stopper has been forced to its place beneath the upper surface of the cap.

A is the body of the bottle.

B is a circumferential bead near the top of the neck of the bottle.

C is a circumferential groove formed beneath bead B.

B' is the top surface of the cap.

B² is a circumferential drop-flange to B'.

B³ is an ear or indent in flange B², which takes under the bead B in groove C to hold the cap against removal by pressure from within the bottle. There are two or more of these ears or indents in said flange B², (generally three.)

D is a central opening in top of cap B'.

E F G H J are details of a bottling-machine in which is placed a stopper I, as shown in Fig. 1, in the act of being forced into the bottle-neck by a plunger after the fluid has been injected in the usual manner.

The details of the filling and corking apparatus herewith shown are in some respects new as adapted to this my invention and are the subject of another application.

The operation of my invention is as follows:

The cap having been placed upon the bottle-

mouth and the ears or indents B³ entered beneath the bead B in groove C, the bottle is placed under the filling and corking tube of a bottling-machine, as shown in Fig. 1, and the fluid under pressure is forced into the 55 bottle through the central opening D in the cap. The stopper is then forced into the bottle-neck entirely beneath the top B' of the cap through opening D by the plunger J compressing the stopper in taper tube H of the 60 corking-machine to a size which will permit it to pass through said opening D and beneath it, as shown in Fig. 2. The stopper then expands to its original size, thus filling the bottle-neck, and the outward pressure of the 65 gases and liquid in the bottle forces the stopper upward against the under side of the top surface B' of the cap and against the walls of the bottle-neck and seals the bottle against leakage. The greater the pressure in the bot- 70 tle the tighter will be the sealing.

Having now fully described my invention and the manner in which I have embodied it, what I claim as new and as my invention, and desire to secure by Letters Patent, is— 75

In a means for sealing vessels containing liquids under pressure, the combination consisting of a vessel provided with a neck and means to receive a cap; a sealing-cap provided with means for securing it over the 80 mouth of said vessel-neck said cap having a substantially flat upper surface, and a central opening in said top surface of less diameter than the inner diameter of the vessel-neck; and a stopper entered beneath the top 85 surface of said cap through the opening in its top surface, whereby the outward pressure of the contents of the vessel force the stopper against the under side of the top surface of said cap and against the inner walls of the 90 vessel-neck to seal the vessel, substantially as hereinbefore specified.

In testimony whereof I have signed my name to this specification, in the presence of two subscribing witnesses, this 14th day of 95 July, 1903.

JAMES MILNOR HICKS.
